UNITED STATES PATENT OFFICE

HAROLD KARL BOUVIER, OF LA GRANGE, ILLINOIS, ASSIGNOR TO TEMPLE CORPORATION, OF CHICAGO, ILLINOIS, A CORPORATION OF DELAWARE

LOUD SPEAKER

Application filed June 15, 1929. Serial No. 371,235.

My invention relates to sound emitting devices or loud speakers of the type commonly employed in connection with radio-receiving sets, or the like.

A particular object of the invention is to provide improved magnetizing structure for a device of the kind described.

Another particular object of the invention is to provide a simplified construction for a device of the kind described.

Still another particular object of the invention is to provide improved devices of the kind described comprising parts which can be assembled quickly and easily, and will remain in alinement even though subjected to relatively hard usage.

Many other objects and advantages will become apparent as this description progresses, reference being had to the accompanying drawings, wherein:

Figure 1 is a central vertical section taken through a loud speaker which embodies the invention;

Fig. 2 is a plan section taken on line 2—2 of Fig. 1;

Fig. 3 is a section taken on line 3—3 of Fig. 1;

Fig. 4 is a perspective view of an improved magnetizing structure forming part of the loud speaker shown in Fig. 4;

Fig. 5 is a perspective view of a lamination which forms part of the magnetizing structure shown in Fig. 4, and

Fig. 6 is a section taken on line 6—6 of Fig. 3.

Referring to the drawings wherein I have shown a loud speaker which embodies a preferred form of the invention, the reference character 10 designates a diaphragm which is operatively connected to an electrical conductor, armature or winding 11 adapted to be connected by suitable electrical conductors (not shown) to the output circuit, or the equivalent, of a radio-receiving set so that it will be subjected to telephonic currents.

The winding 11 is movably supported in an annular magnetic field 13 provided in a magnetizing structure which is identified generally by the reference character 14. The magnetizing structure 14 preferably com-

prises a winding 15 which is connected to any suitable source of electrical current so that it will energize a magnet 16 forming part of the magnetizing structure 14.

The diaphragm 10 may be of any suitable construction, but preferably comprises a conical portion 18 which is preferably formed from paper, or the equivalent, and is preferably apertured at its apex so that it may be secured thereto by a sleeve 20, the sleeve 20 being preferably formed from paper, or a phenolic condensation product. The base of the conical portion 18 is secured by adhesive, or the equivalent, to an annular member 22 which is preferably formed from relatively flexible leather or paper, and has its outer periphery rigidly secured to a supporting member 25. The supporting member 25 preferably comprises an annular flange 26, an apertured frusto-conical portion 27 and a central aperture disc portion 28. The annular member 22 is clamped between the annular flange 26 and a ring 30, bolts 31 being provided to secure the ring 30 and the annular flange 26 to each other. Secured to the outer surface of the ring 30 by adhesive, or the equivalent, is a felt ring 33.

The winding 11 is preferably disposed in an annular groove 35 formed in the sleeve 20, and the sleeve 20 is preferably supported by a member 40 which is preferably stamped from relatively thin sheet metal. As best shown in Figs. 1 and 3, the member 40 is preferably rectangular in form and is preferably provided with a plurality of slots 42 which provide arms 43. The central portion of the member 40 is apertured, and is preferably provided with an integral collar 45 in which the sleeve 20 is secured. A reinforcing flange 46 preferably extends entirely around the periphery of the member 40 and is provided so that the member may be formed of relatively thin sheet metal and so that its edges will not vibrate. Of course, the sheet metal is somewhat resilient, and it is readily apparent that the sleeve 20 is supported by the relatively resilient arms 43 provided in the member 40.

The means for supporting the member 40 comprises a plurality of studs 50 screw-

threaded into apertures 51 in a pole piece 53 which forms part of the magnet 16. As best illustrated in Figs. 2 and 6, the studs 50 project outward from the pole piece 53 and pass 5 through apertured flanges 55 preferably formed integral with a frame member 56. The disc portion 28 of the supporting member 25 is clamped between the flanges 55 and nuts 58 screw-threaded upon the studs 50, and 10 the member 40 is preferably clamped between the nuts 58 and nuts 60 also screw-threaded upon the studs 50.

The magnet 16 preferably comprises a plurality of laminations 65, one of which is 15 shown by itself in perspective in Fig. 5. Each lamination 65 preferably comprises a suitable bar 66 having integral arms 67 projecting from the ends thereof, and at right angles thereto, and projecting from the center 20 of each bar 66 at right angles thereto is an arm 69 which is preferably longer than the arms 67 to provide a pole piece 70 which projects into an aperture 71 provided in the pole piece 53, the annular magnetic field 13 25 being formed between the pole pieces 70 and 53. The ends of the arms 69 of the laminations 65 are preferably turned down in a lathe, or the like, so that the pole piece 70 is cylindrical in form and may be arranged concentrically with respect to the aperture 71 30 which is circular in form.

The several laminations 65 are preferably secured to each other by rivets 75, or the equivalent, and L-shaped bracket members 35 76 are preferably provided for securing the pole piece 53 to the laminations 65. Thus, it will be noted that I have provided four bracket members 76 secured to the laminations 65 by screws 77, the pole piece 53 being 40 secured to the bracket members 76 by screws 78.

While I have shown and described certain embodiments of this invention, it is to be understood that it is capable of many modifications. Changes, therefore, in the construction and arrangement may be made 45 without departing from the spirit and scope of the invention as disclosed in the appended claim, in which it is my intention to claim 50 all novelty inherent in my invention as broadly as possible, in view of the prior art.

What I claim as new is:

A device of the kind described comprising 55 a substantially E-shaped magnet member formed entirely of flat laminations superimposed upon each other, the arms of said magnet member being rectangular in cross-section and the middle arm having its free 60 end formed into a cylindrical pole tip, a plate secured to said E-shaped magnet member and apertured to surround said pole tip, said apertured plate and said pole tip co-operating to provide an annular magnetic field, a 65 diaphragm, and means re-acting with said

magnetic field for actuating said diaphragm.

In witness whereof, I have hereunto set my hand this 5th day of June, 1929.

H. KARL BOUVIER.
